UNITED STATES PATENT OFFICE.

HOWARD H. METCALF, OF BATTLE CREEK, MICHIGAN, ASSIGNOR TO BATTLE CREEK BREAD WRAPPING MACHINE CO., OF BATTLE CREEK, MICHIGAN.

WRAPPING MACHINE.

Application filed July 24, 1925. Serial No. 45,817.

This invention relates to improvements in wrapping machines.

The main objects of the invention are:

First, to provide in a wrapping machine means for introducing an insert or slip of advertising or other matter with the wrapper.

Second, to provide a structure of the class described in which the inserts are automatically fed one at a time and caused to attach to the waxed or paraffined wrapper so that they will not become dislocated during the following wrapping and sealing operations.

Third, to provide in a structure of the class described effective means for feeding and controlling the inserts.

Objects pertaining to details and economies of construction and operation of my invention will definitely appear from the detailed description to follow.

I accomplish the objects of my invention by the devices and means described in the following specification. The invention is clearly defined and pointed out in the claims.

A structure embodying the features of my invention is clearly illustrated in the accompanying drawing forming a part of this application, in which:

30 Fig. I is a fragmentary perspective view of a sealing machine embodying the features of my invention, such portions only of the sealing machine being indicated as to show the relation of my improvements thereto.

35 Fig. II is a side elevation of my improved insert feeding and securing mechanism.

Fig. III is a detail view mainly in vertical section on a line corresponding to line 3-3 of Fig. II.

Fig. IV is a detail view partially in vertical section on a line corresponding to line 4-4 of Fig. II.

45 Fig. V is an enlarged fragmentary perspective view showing structural details.

Fig. VI is a detail longitudinal section on a line corresponding to line 6-6 of Figs. III and V, showing details of the insert feed mechanism, the insert plunger being in its retracted position.

Fig. VII is a detail section corresponding to that of Fig. VI with the insert feed plunger in its fully projected position.

50 Fig. VIII is a fragmentary view showing

details of the insert sealing or affixing mechanism.

Fig. IX is a detail view partially in section on a line corresponding to line 9-9 of Fig. VIII, showing details of the heating unit.

Fig. X is a fragmentary section on a line corresponding to line 10-10 of Fig. V showing details of the affixing mechanism.

Fig. XI is a perspective view of preferred form of insert which consists of a strip having a double fold therein providing a flap-like projection at one end.

Fig. XII illustrates another form of insert having but a single fold providing a flap.

In the drawing the sectional views are taken looking in the direction of the little arrows at the ends of the section lines and similar numerals of reference indicate similar parts throughout the several views.

Referring to the drawing, 1 represents the frame of a wrapping and sealing machine for wrapping articles such as loaves of bread and the like with waxed paper. In practice I have embodied my improvements in the type of machine shown in United States Letters Patent to Brownell, No. 1,416,165, dated May 16, 1922.

55 The sealing mechanism comprises a paper feed mechanism designated generally by the numeral 2 and includes a feed control mechanism designated generally by the numeral 3 which is controlled from a trip 4 operatively associated with the feed belt 5. The trip is mounted on a rockshaft 6 which has an arm 7 thereon connected by the link 8 to the paper feed control mechanism 3 so that the paper feed mechanism is driven only when articles are fed to the machine, the incoming article engaging the trip 4, and, through the mechanism pointed out, setting the paper feed into operation.

60 I have illustrated my improvements as a form of attachment consisting of a main frame 9 which is mounted on the front end of the sealing machine frame. This frame 9 is provided with a support 10 for the paper roll 11. The paper is passed from the roll 11 over a guide roll 12 to the paper feed mechanism 2.

65 Below the path of the web of paper is the hopper 13 for the inserts 14, see Figs. XI and XII, which consist of a slip or sheet having a double fold therein, one fold

providing a flap 15, see Fig. XI. In Fig. XII the insert 16 has a single fold providing a flap 17 corresponding to the flap 15. These inserts are arranged in the hopper 5 one upon the other as shown in Figs. VI and VII with the flaps upwardly and forwardly. The hopper has an adjustable bottom 18 carried by the post 19 which is mounted for vertical movement in a bracket 10 20. The bottom is mounted upon this post 19 for longitudinal tilting adjustment, the same being pivoted at 21 and the pivot being arranged transversely of the machine so that the bottom may tilt to accommodate the 15 varying thickness in the stack of inserts occasioned by the flap fold at one end thereof.

The post 19 is carried by the arm 22 which is pivoted at 23 on the hanger 24, the arm 20 being urged yieldingly upward by the coiled spring 25 to limit the upward movement of the hopper bottom. The post is provided with a notch 26 which is engaged by the dog 27, a notch 28 being provided for holding the bottom in its retracted or lowest 25 position for convenience in filling. This dog engaging the notch 26 prevents the bottom moving upward into the path of the insert feeding plunger 29.

30 The insert feeding plunger 29 is blade-like in form and reciprocates above the hopper, being supported and guided by the ways 30. The plunger, however, in its retracted position lies over a portion of the 35 hopper but is in such a position that on its forward movement it passes under the flap of the insert, see Figs. VI and VII.

To prevent the top insert being pushed 40 or drawn out of the hopper on the retracting movement of the plunger, the plunger shank 32 is provided with a longitudinal slot 33 to receive the upwardly projecting lug 34 on the rear wall 35 of the hopper, see Fig. V, the wall of the hopper, in effect, 45 thus projecting above the plunger,

The plunger is reciprocated by means of the segment 36 coating with the rack 37 on the plunger shank 32. The segment 36 is mounted on a sleeve 38 connected by the 50 pitman 39 to the crank 40 on the shaft 41. The pitman or link 39 is connected to an arm 42 on the sleeve 38'. The driving means for the shaft 38 is controlled by the feeding 55 of the articles to be wrapped, and being operatively connected to the shaft 41, as stated, controls the paper feed.

This driving and control mechanism comprises a clutch mechanism designated generally by the numeral 43 and connected by 60 the link 44 to an arm 45 on the rockshaft 6. The control clutch is connected by the sprocket chain 46 to a sprocket wheel 47 on the shaft 41. This shaft is provided with a crank 48 which is connected by the link 65 49 to the arm 50 on the rockshaft 38 so that

the insert feed mechanism is operated only when articles are being fed to the machine, and also in synchronism with the paper feed mechanism, being as above described operatively associated therewith.

70

The web of paper is fed above the hopper, as stated, and the inserts are fed forwardly by the plunger beneath the web of paper and above the insert supporting or affixing bed 51. This bed 51 has a plate-like extension 52 which, in effect, constitutes a part of the bed.

75

As the inserts are fed from the hopper onto the affixing bed 51 they are carried under the spring finger 53 which has a down-turned end 54 adapted to normally lie below the plane of the bed as shown in Fig. VI, and holding the insert until the plunger has passed under the flap.

80

While the inserts are supported by the bed 51, heat is applied to the web of paper above the flap of the insert melting or warming the paraffin sufficiently so that the insert will adhere to the wrapper. This heating and affixing means comprises the heating roller 55 having a heating unit 56 therein, the roller having an enlarged portion of a length corresponding to the area which it is desired to heat. A pressing roller 57 follows the heating roller, see details illustrated in Figs. VI and VII.

85

The heating roller is provided with a shaft 58 carried by the arms 59 on the rod 60 which has rollers 61 traveling in opposed ways 62. This rod 60 constitutes a carriage.

90

The cooling and pressing roller 57 is carried by arms 63 on this carriage 60. The carriage is non-rotatably supported and carries arms 64 constituting thrust members for the springs 65 which are supported on the rods 66' arranged through the arms 64.

95

The carriage 60 is provided with arms 66 constituting thrust members for the springs 67 carried by the rods 68 applying pressure to the roller 57. The carriage 60 is connected by the links 69 to the cross rod 70 carried by the arm 50 and a corresponding arm 50' on the opposite side of the machine so that the heating and pressing rollers are actuated in synchronism with the one mechanism.

100

The heating and pressing rollers are controlled to be brought into and out of operating position by means of the cam rockers 71 which are pivoted at 72 to provide tracks for the rollers 73 and 74 on the roller shafts 58 and 74', respectively. These cam tracks are rocked by means of the cams 75 acting on the arms 76 pivoted at 77, the cam tracks being connected to the arms by means of the links 78 so that the heating and affixing rollers are lifted on their return stroke. The parts are proportioned so that the heating roller passes off the end of the feed

105

110

115

120

125

130

plunger on its forward stroke, thereby limiting its pressure engagement with the web of paper and permitting the pressing roller to travel over substantially the same surface 5 as that covered by the heating roller.

For convenience in making the electrical connections to the heating unit, the roller 73 at one end is carried by a rod 79 mounted on the arm 59 and carrying a bracket 80 10 for the left-hand roller 73. The brushes 81 are mounted on this rod 79 to coact with the contact rings 82 for the heating unit, see Figs. VIII and IX.

The controlling cam track 71 for the affixing rollers hold the pressure roller in operative relation until approximately the point at which heat has been applied is reached, and when they come into engagement with the web of paper press the heated 20 web upon the flap of the insert while the insert is supported by the feed plunger. The heating roller passing beyond the end of the feed plunger leaves the web for there is not sufficient contact between the web and 25 the roller to materially heat the paraffin of the web.

The lifting of the cam tracks 71 is timed so that on the return stroke of the affixing carriage the rollers are out of contacting 30 position. These movements are all properly timed or synchronized.

My improved insert affixing means affixes an insert to each wrapper so that when the wrapper is applied to the article, the insert 35 is enclosed, thus enabling the introduction of advertising and descriptive matter, directions for use, recipes, or the like, as may be desired.

I have illustrated and described my improvements in an embodiment which I have found very practical. I have not attempted 40 to illustrate or describe various embodiments or adaptations as I believe the disclosure made will enable those skilled in the art 45 to which my invention relates to embody or adapt my improvements as may be desired.

Having thus described my invention what I claim as new and desire to secure by Letters Patent is:

50 1. In a structure of the class described, the combination with paper feed means, of an insert mechanism comprising a hopper disposed below the path of the paper and having a spring supported pivotally mounted bottom, a table at the rear of said hopper, a blade-like insert feed plunger reciprocating above the hopper and table, said feed plunger having a longitudinally slotted shank, the rear wall of said hopper having a part projecting into said 55 slot, a spring insert retaining finger mounted above said plunger and adapted to rest upon the rear edge of the top insert in the hopper when the plunger is in retracted position, a reciprocating carriage provided with independent pivoted spring pressed arms, heating and pressing rollers mounted on said arms for independent vertical movement, pivoted cam tracks for said heating and pressing rollers whereby on the forward stroke of the 60 carriage the pressing roller is caused to engage the work at approximately the point of engagement of the heating roller therewith, actuating cams for said cam tracks acting to hold said heating and pressing rollers in 65 inoperative relation on the return stroke of the carriage, operating connections for said plunger, carriage and cam track control cams whereby the actuating thereof is timed to cause the heating and pressing rollers to act 70 while the insert is supported by said plunger, article controlled driving means for said paper feed means, and article controlled driving means for said insert mechanism.

2. In a structure of the class described, 75 the combination with paper feed means, of an insert mechanism comprising a hopper, a blade-like insert feed plunger reciprocating above the hopper and table, a reciprocating carriage provided with independent pivoted spring pressed arms, heating and pressing rollers mounted on said arms for independent vertical movement, pivoted cam tracks for said heating and pressing rollers whereby on the forward stroke of the carriage the pressing roller is caused to engage the work at approximately the point of engagement of the heating roller therewith, actuating cams for said cam tracks acting to hold said heating and pressing rollers in 80 inoperative relation on the return stroke of the carriage, operating connections for said plunger, carriage and cam track control cams whereby the actuating thereof is timed to cause the heating and pressing rollers to act 85 while the insert is supported by said plunger, article controlled driving means for said paper feed means, and article controlled driving means for said insert mechanism.

2. In a structure of the class described, 90 the combination with paper feed means, of an insert mechanism comprising a hopper, a blade-like insert feed plunger reciprocating above the hopper and table, a reciprocating carriage provided with independent pivoted spring pressed arms, heating and pressing rollers mounted on said arms for independent vertical movement, pivoted cam tracks for said heating and pressing rollers whereby on the forward stroke of the carriage the pressing roller is caused to engage the work at approximately the point of engagement of the heating roller therewith, actuating cams for said cam tracks acting to hold said heating and pressing rollers in 95 inoperative relation on the return stroke of the carriage, operating connections for said feed plunger, carriage and cam track control cams whereby the actuating thereof is timed to cause the heating and pressing rollers to act 100 while the insert is supported by said plunger, article controlled driving means for said paper feed means, and article controlled driving means for said insert mechanism.

3. In a structure of the class described, 110 the combination with paper feed means, of an insert hopper disposed below the path of the paper and having a spring supported pivotally mounted bottom, a table at the rear of said hopper, a blade-like insert feed plunger reciprocating above the hopper and table, said feed plunger having a longitudinally slotted shank, the rear wall of said hopper having a part projecting into said 115 slot, a spring insert retaining finger mounted above said plunger and adapted to rest upon the rear edge of the top insert in the hopper when the plunger is in retracted position, a reciprocating carriage provided with independent pivoted spring pressed arms, heating and pressing rollers mounted on said arms for independent vertical movement, pivoted cam tracks for said heating and pressing rollers whereby on the forward stroke of the carriage the pressing roller is 120 125 130

caused to engage the work at approximately the point of engagement of the heating roller therewith, actuating cams for said cam tracks acting to hold said heating and pressing rollers in inoperative relation on the return stroke of the carriage, and operating connections for said feed plunger, carriage and cam track control cams whereby the actuating thereof is timed to cause the heating and pressing rollers to act while the insert is supported by said plunger.

4. In a structure of the class described, the combination with paper feed means, of an insert hopper, a table at the rear of said hopper, a blade-like insert feed plunger reciprocating above the hopper and table, a reciprocating carriage provided with independent pivoted spring pressed arms, heating and pressing rollers mounted on said arms for independent vertical movement, pivoted cam tracks for said heating and pressing rollers whereby on the forward stroke of the carriage the pressing roller is caused to engage the work at approximately the point of engagement of the heating roller therewith, actuating cams for said cam tracks acting to hold said heating and pressing rollers in inoperative relation on the return stroke of the carriage, and operating connections for said feed plunger, carriage and cam track control cams whereby the actuating thereof is timed to cause the heating and pressing rollers to act while the insert is supported by said plunger.

5. In a structure of the class described, the combination with paper feed means, of an insert mechanism comprising a hopper having a spring supported pivotally mounted bottom, a table at the rear of said hopper, an insert feed plunger delivering to said table, a yielding insert retaining finger adapted to engage the top insert in the hopper when the plunger is in retracted position, a reciprocating carriage; heating and pressing rollers mounted on said carriage for independent vertical movement, adjustably mounted cam tracks for said heating and pressing rollers whereby on the forward stroke of the carriage the pressing roller is raised to engage the work at approximately the point of engagement of the heating roller therewith, actuating means for said cam tracks acting to hold said heating and pressing rollers in inoperative relation on the return stroke of the carriage, and operating connections for said feed plunger, carriage and cam track actuating means whereby the actuating thereof is timed to cause the heating and pressing rollers to act while the insert is supported by said plunger.

6. In a structure of the class described, the combination with paper feed means, of

an insert mechanism comprising a hopper, a table at the rear of said hopper, an insert feed plunger delivering to said table, a reciprocating carriage, heating and pressing rollers mounted on said carriage for independent vertical movement, adjustably mounted cam tracks for said heating and pressing rollers whereby on the forward stroke of the carriage the pressing roller is raised to engage the work at approximately the point of engagement of the heating roller therewith, actuating means for said cam tracks acting to hold said heating and pressing rollers in inoperative relation on the return stroke of the carriage, operating connections for said feed plunger, carriage and cam track actuating means whereby the actuating thereof is timed to cause the heating and pressing rollers to act while the insert is supported by said plunger, article controlled driving means for said paper feed means, and article controlled driving means for said insert mechanism.

7. In a structure of the class described, the combination with paper feed means, of an insert hopper having a spring supported pivotally mounted bottom, a table at the rear of said hopper, an insert feed plunger delivering to said table, a yielding insert retaining finger adapted to engage the top of the insert in the hopper when the plunger is in retracted position, a reciprocating carriage, heating and pressing rollers mounted on said carriage for independent vertical movement, adjustably mounted cam tracks for said heating and pressing rollers whereby on the forward stroke of the carriage the pressing roller is raised to engage the work at approximately the point of engagement of the heating roller therewith, actuating means for said cam tracks acting to hold said heating and pressing rollers in inoperative relation on the return stroke of the carriage, and operating connections for said feed plunger, carriage and cam track actuating means whereby the actuating thereof is timed to cause the heating and pressing rollers to act while the insert is supported by said plunger.

8. In a structure of the class described, the combination with paper feed means, of an insert hopper, a table at the rear of said hopper, an insert feed plunger delivering to said table, a reciprocating carriage, heating and pressing rollers mounted on said carriage for independent vertical movement, adjustably mounted cam tracks for said heating and pressing rollers whereby on the forward stroke of the carriage the pressing roller is raised to engage the work at approximately the point of engagement of the heating roller therewith, actuating means for said cam tracks acting to hold said heating and pressing rollers in inoperative relation on the return stroke of the carriage,

and operating connections for said feed plunger, carriage and cam track actuating means whereby the actuating thereof is timed to cause the heating and pressing 5 rollers to act while the insert is supported by said plunger.

to provide flaps to paraffined paper, the combination of a paper feed means, an insert hopper disposed at the side of the path of the paper and having a pivotally mounted yieldingly supported bottom acting to urge 70 the inserts toward the path of the paper, a table, a feed plunger adapted upon actuation to engage beneath the flap of the top insert carrying the same upon the table, a reciprocating carriage, and heating and pressing 75 members on said carriage.

9. In a device for affixing inserts folded to provide flaps to paraffined paper, the combination of an article controlled paper feed 10 means, an insert hopper disposed at the side of the path of the paper and having a pivotally mounted yieldingly supported bottom acting to urge the inserts toward the path of the paper, a table, a feed plunger adapted upon actuation to engage beneath the flap of the top insert carrying the same upon the table, a reciprocating carriage, 15 heating and pressing members mounted on said carriage for independent vertical movement, means for causing said heating and pressing members to engage the paper opposite the insert flap at approximately the same point on the forward stroke of the carriage and while the insert flap is supported by the plunger and to hold said heating and pressing members out of contact with the paper on the return stroke of the carriage, and article controlled actuating 20 means for said plunger and carriage.

13. In a structure of the class described, the combination with paper feed means, of an insert feeding mechanism adapted to feed inserts folded to provide a flap comprising an insert hopper having a yieldingly supported pivotally mounted bottom, a table at the rear of said hopper, a feed plunger reciprocating across said hopper and adapted 25 when in its retracted position to overlie the hopper with the top insert thereof engaging the under side of the plunger with its flap lying at the front of the plunger, a spring finger resting upon the rear edge of the top insert in the hopper when the plunger is 30 in its retracted position, and affixing means timed to act while the insert flap is supported by the projected plunger.

10. In a device for affixing inserts folded to provide flaps to paraffined paper, the combination of a paper feed means, an insert hopper disposed at the side of the path of the paper and having a pivotally mounted yieldingly supported bottom acting to urge 35 the inserts toward the path of the paper, a table, a feed plunger adapted upon actuation to engage beneath the flap of the top insert carrying the same upon the table, a reciprocating carriage, heating and pressing 40 members mounted on said carriage for independent vertical movement, and means for causing said heating and pressing members to engage the paper opposite the insert flap at approximately the same point on the forward stroke of the carriage and while the insert flap is supported by the plunger and to hold said heating and pressing members out of contact with the paper on the return 45 stroke of the carriage.

14. In a structure of the class described, the combination with paper feed means, of an insert feeding mechanism adapted to feed inserts folded to provide a flap, a table at the rear of said hopper, a feed plunger reciprocating across said hopper and adapted 50 when in its retracted position to overlie the hopper with the top insert thereof engaging the under side of the plunger with its flap lying at the front of the plunger, and affixing means timed to act while the insert flap is supported by the projected 55 plunger.

11. In a device for affixing inserts folded to provide flaps to paraffined paper, the combination of paper feed means, an insert hopper disposed at the side of the path of the paper and having a pivotally mounted yieldingly supported bottom acting to urge 60 the inserts toward the path of the paper, a table, a feed plunger adapted upon actuation to engage beneath the flap of the top insert carrying the same upon the table, a reciprocating carriage, heating and pressing 65 members on said carriage, and article controlled actuating means for said plunger and carriage.

15. In a structure of the class described, the combination with paper feed means, of an insert feeding mechanism adapted to feed inserts folded to provide a flap comprising an insert hopper having a yieldingly supported pivotally mounted bottom, a table at the rear of said hopper, a feed plunger 70 engaging the inserts beneath the flaps thereof, a spring finger resting upon the rear edge of the top insert in the hopper when the plunger is in its retracted position, and affixing means timed to act while the insert flap is supported by the projected plunger.

12. In a device for affixing inserts folded to provide flaps to paraffined paper, the combination of a paper feed means, an insert hopper disposed at the side of the path of the paper and having a pivotally mounted yieldingly supported bottom acting to urge 75 the inserts toward the path of the paper, a table, a feed plunger adapted upon actuation to engage beneath the flap of the top insert carrying the same upon the table, a reciprocating carriage, heating and pressing 80 members mounted on said carriage for independent vertical movement, and means for causing said heating and pressing members to engage the paper opposite the insert flap at approximately the same point on the forward stroke of the carriage and while the insert flap is supported by the plunger and to hold said heating and pressing members out of contact with the paper on the return stroke of the carriage.

16. In a structure of the class described, the combination with paper feed means, of an insert feeding mechanism adapted to feed inserts folded to provide a flap, a feed plunger engaging the inserts beneath the flaps thereof, and affixing means timed to 85 act while the insert flap is supported by the plunger.

17. In a device for affixing inserts to paraffined paper wrappers, the combination of an article controlled paper feed means, 90

a table, means for feeding inserts one by one to said table, a reciprocating carriage, heating and pressing members mounted on said carriage for independent vertical movement, 5 means for causing said heating and pressing members to engage the paper opposite the insert at approximately the same point on the forward stroke of the carriage, and to hold said heating and pressing members out 10 of contact with the paper on the return stroke of the carriage, and article controlled actuating means for said plunger and carriage.

18. In a device for affixing inserts to 15 paraffined paper wrappers, the combination of paper feed means, a table, means for feeding inserts one by one to said table, a reciprocating carriage, heating and pressing members mounted on said carriage for 20 independent vertical movement, and means for causing said heating and pressing members to engage the paper opposite the insert at approximately the same point on the forward stroke of the carriage, and to hold 25 said heating and pressing members out of contact with the paper on the return stroke of the carriage.

19. In a device for affixing inserts folded to provide flaps to paraffined paper, the 30 combination of paper feed means, an insert hopper having a pivotally mounted yieldingly supported bottom acting to urge the inserts toward the path of the paper, a table, a blade-like feed plunger adapted 35 upon actuation to engage beneath the flap of an insert carrying the same upon the table, a reciprocating carriage, and heating and pressing means engaging the paper opposite the insert flap and while the flap is 40 supported by the plunger.

20. In a device for affixing inserts folded to provide flaps to paraffined paper, the combination of paper feed means, an insert hopper, a table, a blade-like feed plunger 45 adapted upon actuation to engage beneath the flap of an insert carrying the same upon the table, a reciprocating carriage, and heating and pressing means engaging the paper opposite the insert flap and while the flap is 50 supported by the plunger.

21. In a device for affixing inserts folded to provide flaps to paper, the combination of paper feed means, an insert hopper having a pivotally mounted yieldingly supported bottom acting to urge the inserts toward the path of the paper, a table, a feed plunger adapted upon actuation to engage beneath the flap of an insert carrying the same upon the table, a reciprocating carriage, and affixing means timed to act while the label is supported by the table.

22. In a device for affixing inserts folded to provide flaps to paper, the combination

of paper feed means, an insert hopper, a table, a feed plunger adapted upon actuation to engage beneath the flap of an insert carrying the same upon the table, a reciprocating carriage, and affixing means. 65

23. In a device for affixing inserts, the combination of paper feed means, a table, means for feeding inserts one by one to said table, heating and pressing members mounted for independent movement, and means for actuating said heating and pressing members to engage the paper opposite the 75 insert at approximately the same point.

24. The combination with a wrapping machine including article controlled paper feed means, of an insert feeding mechanism adapted to deliver the inserts one by one in 80 contacting relation to the paper, means for heating contacting portions of the paper and pressing the same upon the insert to affix the insert to the paper by means of the 85 paraffin of the paper, and article controlled actuating means for said insert feeding and affixing means.

25. The combination in a structure of the class described, of article controlled means 90 for feeding paraffined paper, means for feeding inserts into contacting relation to the paper, and means for heating contacting portions of the paper to affix the inserts to the paper, said feeding and heating means being article controlled. 95

26. The combination with a wrapping machine including paper feed means, of an insert feeding mechanism adapted to deliver the inserts one by one into contacting relation to the paper, and means for heating contacting portions only of the paper and pressing the same upon the insert to affix 100 the insert to the paper by means of the paraffin of the paper.

27. The combination in a structure of the class described, of means for feeding paraffined paper, means for feeding inserts into contacting relation to the paper, and means for heating contacting portions only of the paper to affix the inserts to the paper. 105

28. The combination with a wrapping machine including article controlled paper feed means, of an insert feeding mechanism adapted to deliver the inserts one by one in contacting relation to the paper, and article controlled affixing means. 110

29. The combination in a structure of the class described, of article controlled means for feeding paper, means for feeding inserts into contacting relation to the paper, and means for affixing the inserts to the paper, said insert feeding and affixing means being article controlled. 120

In witness whereof I have hereunto set my hand.

HOWARD H. METCALF.
